(57) **CLAIM**

The ornamental design for a dispenser, as shown and described.

DESCRIPTION

FIG. 1 is a perspective view of a dispenser showing the new design,

FIG. 2 is a left side elevation view of FIG. 1,

FIG. 3 is a right side elevation view of FIG. 1,

FIG. 4 is front elevation view of FIG. 1,

FIG. 5 is a rear elevation view of FIG. 1,

FIG. 6 is a top plan view of FIG. 1; and,

FIG. 7 is a bottom plan view of FIG. 1.

Broken lines are included for the purpose of illustration portions of the dispenser that form no part of the design.

1 Claim, 4 Drawing Sheets
